UNITED STATES PATENT OFFICE.

JOSEPH URBANEK, OF CHICAGO, ILLINOIS.

CAR-INDICATOR.

1,312,146.

Specification of Letters Patent.

Patented Aug. 5, 1919.

Application filed April 11, 1919. Serial No. 289,306.

To all whom it may concern:

Be it known that I, JOSEPH URBANEK, a citizen of Austria, residing at Chicago, county of Cook, and State of Illinois, have 5 invented certain new and useful Improvements in Car-Indicators, of which the following is a specification.

This invention relates to improvements in devices for indicating the location at which 10 a car will next stop.

The principal object of the invention is to provide a device which may be attached to cars of the ordinary type of construction without change therein, and which will automatically indicate the next stopping place 15 of the car by disclosing a blank on which the name of the stopping place or street intersection is shown.

A further object is to combine with the 20 apparatus track side devices whereby such disclosure is accomplished without the aid of the operators of the car.

These and other like objects are attained by the novel construction and combination 25 of parts hereinafter described, and shown in the accompanying drawings, forming a material part of this disclosure, and in which—

Figure 1 is a side elevational view showing 30 a conventional type of car, and indicating the application of the invention, parts being broken away in order to disclose the interior construction.

Fig. 2 is a vertical sectional view taken on 35 line 2—2 of Fig. 1.

Fig. 3 is an enlarged fragmentary view showing the operating means, the cover plate by which they are concealed being removed.

Fig. 4 is an enlarged fragmentary sectional view showing the roller operating devices by which the stations are disclosed.

Fig. 5 is a fragmentary sectional view taken on line 5—5 of Fig. 4.

Fig. 6 is an enlarged fragmentary side elevational view showing the front portion of the side connections.

Fig. 7 is a horizontal sectional view taken on line 7—7 of Fig. 1, and

Fig. 8 is a horizontal sectional view taken on line 8—8 of Fig. 3.

Referring to the drawings, the numeral 10 indicates a conventional type of street car, mounted upon wheels 11, resting upon a pair 55 of running rails 12, all of the foregoing

parts being of the usual type of construction.

Secured below the platform of the car 10, at the ends thereof, are brackets 14, inclosed in casings 15, while below the center of the 60 car is another casing 18, provided with a pair of oppositely disposed brackets 19, in which are rotatably mounted spindles 20, carrying pairs of spur gears 21 and 22. These gears are engaged with a rack bar 23, 65 having teeth upon opposite sides, the upper teeth engaging with the teeth of the gears, while the lower teeth engage with the teeth of a segment 24, pivoted on a pin 25, carried in an extension 26 of the casing 18. 70

The segment is operated by an extending lever 27, in which is rotatably engaged, at its lower end a roller 28.

The teeth of the gears 20 and 21 are also engaged with another single rack 30 guided 75 in the casing 18, both the racks being normally held in a central position, due to the effect of the coiled compression springs 31 and 32, these springs encircling rods 34 and 35, the same being arranged in offset pairs, 80 one over the other, and terminating in racks 36 and 37, arranged to actuate gears 40, freely mounted on spindles 41, carried in the brackets 14.

Arranged to the side of the gears 40 are 85 ratchet wheels 42, operated by spring impelled dogs 43, so as to communicate rotary motion in one direction only to the spindles 41.

Secured to the ends of the spindles 41 are 90 bevel gears 44, meshing with pinions 45, adapted to communicate rotary movement to vertical rods 46, having bevel pinions 47 at their upper ends engageable with other bevel gears 48, fixed upon the shafts 50, 95 rotatably mounted on the casings 51, attached respectively at the inner ends of the car, and driving crown gears 52. The gears in turn communicate motion, either direct or indirect, to spur gears 54, mounted on vertical spindles 55, which have attached to them drums 57, having flanged ends 58, and carrying a coil of fabric 60 upon which are the names of the stations.

The strip 60 as it is moved, is held to the 105 front of the casing, in which is an aperture 61, by rods 62, so that the names can be easily seen from either end of the car.

The track side connections by which this mechanism is operated, consists of a pair 110

of rail side bars 70, normally pressed upward by coiled compression springs 71, arranged at each end thereof, the ends 72 of the bars being downturned.

5 Engaged centrally between the ends of the bars 70, are brackets 73 in which are short levers 74, pivoted at their outer ends by pins 75. These levers are engaged near the center of their length by transmission 10 links 76, which in turn are connected at their opposite ends to other levers 78, pivoted below the rail, the links 76 engaging with transverse bars 79, so as to cause a center bar 82 to be raised or elevated as the side bars 15 70 are depressed.

When the center bar 82 which is provided with downturned ends 83 is in a raised position, it is adapted to engage with the roller 28, moving the segment 24 and due to engagement with the racks and pinions, moving the bars 34 and 35 in opposite directions, and through the train of gearing before described, actuating the register in an obvious manner.

25 When the car has passed the bars 70 they will be raised by the action of the springs 71, causing the contact bar 82, centrally between the rails, to drop into such position as to permit the roller to pass without making contact. The flanges of the wheels 11 make contact with the normally raised bars 70 so that the gearing employed causes an actuation of the register.

Having thus described my invention what 35 I claim as new, and desire to secure by Letters Patent, is—

1. In a street car registering device, the combination with a pair of indicators at both ends of the car, geared connections extending downward below the platform thereof, a pair of rods slidably mounted below the platform, racks formed with said rods, pinions intervening between said racks, a segment moving the lowermost of said racks, 40 45 a roller carried at the extending ends of said segment, and track-side connections adapted to engage with said roller when the wheels of the car pass thereover.

2. In a street car registering device, the

combination with a pair of indicators arranged at the ends within the body of the car, a pair of racks, one having teeth upon opposite sides disposed below the platform of the car, means for normally holding said racks in a central position, rods extending from said racks at the front and rear of said car, operative connections between said rods and said indicators whereby they are operated, a segment engaging with the lower teeth on one of said racks, a lever extending from said segment, a roller carried by said lever, a pair of bars arranged closely contiguous to the rails over which the car runs, a single bar mounted centrally between said rails, means for holding the first named bars in a normally raised position, said bars being adapted to be depressed by the passage of the car wheel, and connections between the first named bars and said center bars whereby the latter is raised, when the first named bars are depressed, so as to come into contact with said roller.

3. In a car indicator operating device, the combination with a pair of indicators adapted to indicate stations arranged at each end of a car, a casing suspended below said car, a pair of racks slidably longitudinally in said casing, means for holding said racks in a normal central position, pinions engaging between said racks whereby they are caused to move in opposite directions, teeth upon the lowermost rack, a segment pivotally mounted on said casing adapted to engage with the lower teeth of said rack, a lever extending downwardly from said segment, a roller carried thereon, a bar arranged between the rails over which the car passes, means for automatically raising said bar whereby said roller is brought in contact and said rack operated simultaneously, means for diverting the longitudinal reciprocating motion of said racks into rotary motion in one direction only, and connections between said racks and said indicators whereby they are actuated intermittently.

In testimony whereof I have affixed my signature.

JOSEPH URBANEK.
